Specification for Design.

Patented May 6, 1913.

Application filed January 10, 1913. Serial No. 741,322. Term of patent 14 years.

To all whom it may concern:

Be it known that I, SAMUEL L. ALLEN, a citizen of the United States, and a resident of Moorestown, county of Burlington, and State of New Jersey, have invented a new, original, and ornamental Design for a Lever, of which the following is a specification, reference being had to the illustrations shown in the accompanying drawing, in which—

Figure 1 is a plan view of the lever. Figs. 2, 3, and 4, are sectional views taken

transversely as indicated by the broken lines in Fig. 1, the respective figures corresponding to the broken section lines most closely adjacent thereto.

What I claim is:

The ornamental design for a lever substantially as shown.
